UNITED STATES PATENT OFFICE.

BENJAMIN FRANKLIN DAVIES, OF UNION HILL, NEW JERSEY, ASSIGNOR TO L. STRAUS & SONS, OF NEW YORK, N. Y., A FIRM.

DESIGN FOR A GLASS VESSEL.

40,742.

Specification for Design.

Patented June 28, 1910.

Application filed April 20, 1910. Serial No. 556,650. Term of patent 14 years.

To all whom it may concern:

Be it known that I, BENJAMIN FRANKLIN DAVIES, a citizen of the United States, residing in the city of Union Hill, in the county of Hudson and State of New Jersey, have invented a new, original, and ornamental Design for a Glass Vessel, the same being disclosed in the accompanying drawings, in which the figure is an elevation.

I claim:

The ornamental design for a glass vessel, as shown.

BENJAMIN FRANKLIN DAVIES.
